UNITED STATES PATENT OFFICE.

CHARLES WEINBERG, OF NEW YORK, N. Y., ASSIGNOR TO C. WEINBERG & CO., OF NEW YORK, N. Y., A CORPORATION OF NEW YORK.

DESIGN FOR A CURTAIN-EDGING.

No. 40,167.

Specification for Design.

Patented July 20, 1909.

Application filed May 27, 1909. Serial No. 498,776. Term of patent 7 years.

To all whom it may concern:

Be it known that I, CHARLES WEINBERG, a citizen of the United States of America, residing in the borough of Manhattan, city, county, and State of New York, have invented a new, original, and ornamental Design for Curtain-Edgings, of which the following is a specification, reference being had to the accompanying drawing, which forms part thereof.

The figure is a plan view of the curtain edging embodying my new design.

I claim:

The ornamental design for a curtain edging as shown.

CHARLES WEINBERG.
